(57) **CLAIM**

The ornamental design for a USB flash drive, as shown and described.

DESCRIPTION

FIG. 1 is a top, front, left perspective view of a USB flash drive in an inserted position.

FIG. 2 is a perspective view of a USB flash drive in an extracted position, showing the bottom, front, right of the USB flash drive and the top, front, left of its carrier.

FIG. 3 is an enlarged, top, rear, right perspective view of a USB flash drive in an inserted position.

FIG. 4 is an enlarged, top, rear, right perspective view (from the front) of a USB flash drive in an extracted position

FIG. 5 is a top, front, right perspective view of a USB flash drive in an inserted position, shown separately for ease of illustration.

FIG. 6 is a top, front, right perspective view of a USB flash drive in an extracted position, shown separately for ease of illustration.

FIG. 7 is an enlarged, bottom, front, left perspective view of a USB flash drive in an inserted position, shown separately for ease of illustration; and,

FIG. 8 is an enlarged, bottom, front, left perspective view of a USB flash drive in an extracted position, shown separately for ease of illustration.

The broken line showing is included for the purpose of illustrating environmental structure and forms no part of the claimed design.
